PROCESS FOR TINTING LAUNDRY CHEMICALS
IN THE DRY STATE

William A. Millsaps, Philadelphia, and Julian L. Staubly, Oreland, Pa., assignors to Pennsalt Chemicals Corporation, Philadelphia, Pa., a corporation of Pennsylvania
No Drawing. Filed May 10, 1960, Ser. No. 27,987
4 Claims. (Cl. 252—135)

This invention is directed to a process for tinting laundry chemicals.

For many years laundry sours have been tinted with a blue dye. This blue color was obtained by dispersing a pigment dye of the proper tint in water and metering the dispersed dye in the desired proportions to wet zinc silicofluoride, usually in the form of a wet cake following deliquoring of a crystal slurry. Following the addition of the aqueous dye dispersion the wet zinc silicofluoride was blended and dried, usually in a rotary kiln, to yield tinted crystals having a uniform light blue color.

The needs of commercial laundries today are so diverse that normally a single manufacturer will no longer produce all of the chemicals required by laundries but will buy them from other producers and repackage them for resale. For example, today a laundry will use soda ash, sodium tripolyphosphate, sodium hydroxide as neutralizing agents, detergents and soap builders. The fluosilicates, sodium bifluoride and ammonium chloride find use alone or in combination as laundry sours. To assist the commercial laundry user in identifying these different chemicals in the laundry room the manufacturer or supplier now tints these various chemicals.

The water insoluble dyes and pigments used for tinting laundry chemicals are conveniently supplied by the dye manufacturers as aqueous dispersions. These dispersions are quite concentrated and are usually in paste form.

When we applied these concentrated dye pastes to the dry laundry sours and alkalis and blended them, we did not obtain uniformly colored materials. We then found that this difficulty could be overcome by adding larger quantities of water. This resulted in satisfactory tinting of the chemicals, but it made them so wet that they could not be packaged and stored without a subsequent drying operation. Since it was necessary to avoid a separate drying operation, some other means were then sought to secure satisfactory tinting of these laundry chemicals.

We have now discovered that if the dye paste is added to a liquid wetting agent and then blended with the laundry chemical, satisfactory tinting of these chemicals can be obtained. This eliminates the necessity of adding large quantities of water which wet the product and which must then be removed by a drying operation.

We have found that a least 0.25 parts by weight of dye paste is required to color 10,000 parts by weight of a laundry chemical such as a laundry sour or alkaline detergent provided that this amount of dye is dispersed in a wetting agent. The minimum amount of wetting agent needed to disperse this amount of dye is 0.25 part by weight per 10,000 parts by weight of the laundry chemical being tinted. Hence it will be seen that the preferred minimum ratio of dye parts and liquid wetting agent is a weight ratio of 1:1. Larger amounts of dye can be used to secure a deeper tint according to the desires of the user. Similarly, larger amounts of wetting agent may be used. However, no significant advantages are obtained with larger amount of wetting agent except added costs. Moreover, if too much of the wetting agent is added to the laundry chemical, the product will become soggy and caked and will be unsuitable for packaging and storage.

Satisfactory dyes and pigments which we have used

2

to tint laundry chemicals are copper tetrabenzo-porphyrazine pigment, Color Index No. 74,160 (e.g. Helio-Gen Blue BA—CF paste), polychloro copper tetrabenzo-porphyrazine dye pigment, Color Index No. 74,260 (e.g. 5 Calcotone Green G paste), 3-hydroxy-4-(4-nitrotolyl-2-azo) 2-naphthalanilide, a scarlet dye, and calcined iron oxide pigment (e.g. Calcotone Red-MB paste).

Other dyes and pigments in powder or paste form similar to those enumerated above, will suggest themselves to the worker skilled in the art.

The wetting agents which have been found to be satisfactory in dispersing these dye paste concentrates in the laundry chemicals may be a liquid of either a nonionic, cationic or anionic type. Representative nonionic wetting agents which we have found satisfactory for this purpose are the polyethylene glycol alkylphenyl ethers of which the ethylene oxide condensate of nonyl phenol (average of 10 ethylene oxide units) is representative. An ester type of nonionic wetting agent is sorbitan monooleate sold under the trade name Span 80 by Atlas Powder Company. A cocoanut fatty acid alkylol amide condensate, another nonionic wetting agent which has been satisfactorily used in conjunction with the tinting of laundry chemicals is the Alrosol C sold by the Alrose Chemical Company.

Two tertiary amine type of cationic wetting agents which we have used for this purpose are Ethomeen S/15 and Ethomeen 18/15. These are soybean and stearyl amine polyoxyethylene condensates (respectively) in which either the stearyl or soybean alkyl group and two polyoxyethylene groups totaling 5 ethylene oxide groups are attached to the nitrogen atoms.

The anionic wetting agents are also satisfactory for tinting laundry chemicals. Castor oil sulfonate and Sulfonate O.S., a mixed alkyl aryl sulfonate having the empirical formula $C_{25}H_{40}SO_3Na$ are examples of this type of wetting agent that we have used.

While as little as 0.25 part of the dye and 0.25 part of the wetting agent per 10,000 parts of the laundry chemical are satisfactory for tinting of the chemicals, it is preferred to add the materials at a slightly higher concentration. A preferred amount of dye would be 0.2 part by weight per 1000 of laundry chemical (equivalent to 2 parts by weight per 10,000 parts by weight 40 of laundry chemical), with 3.0 parts by weight of liquid wetting agent per 1,000 parts by weight of laundry chemical (equivalent to 30 parts by weight of liquid wetting agent per 10,000 parts by weight of laundry chemical). Hence it will be seen that the preferred maximum ratio of dye parts to liquid wetting agent is .2 in 3 or 2 in 30 or a weight ratio of 1:15. A convenient way of adding the wetting agent and dye to the laundry chemical is to mix the dye paste with an equal part by weight of the wetting agent in a suitable dispersing apparatus. Thereafter, an additional quantity of wetting agent may be added to the mixture which is then added to the laundry chemical in a blending apparatus such as a sigma arm mixer, ribbon blender or conical mill blender. The mixing is continued for a sufficient time, 50 usually about 10 minutes, for the laundry chemical to obtain a uniform hue or tint corresponding to the dye being used.

When the dye is added by itself to the laundry chemical without the addition of the wetting agent, the dye deposits as a colored speck or impurity in the chemical and will not tint to any extent whatsoever. However, when suitably mixed in a wetting agent, the small amount of dye will readily color a large quantity of laundry chemical.

It will be apparent to those skilled in the art that other components in laundry chemicals may be added or

incorporated in the composition without detracting from the efficacy of the tinting process. For examples drying agents, anti-caking agents and perfumes are often incorporated into laundry chemicals, and these will not interfere with the tinting process described above.

The letters "C.I." refer to a standard color index published by Society of Dyers and Colors, 30 Pearl Assurance Building, Bradford, Yorkshire, England, 1922-24 edition. These letters identify a chemical type rather than a shade.

C.I. 74,160 identifies the copper derivative of tetrabenzoporphyrazine.

C.I. 74,260 identifies the polychloro copper derivative of tetrabenzoporphyrazine containing 15 to 16 chlorine atoms.

The best mode of practicing our invention will become apparent as set forth in the following examples in which the parts are by weight and which are given by way of illustration and not by way of limitation.

Example 1

The following mixture of laundry sours was tinted with calcined iron oxide dye paste purchased under name of Calcotone Red MB paste using the nonionic wetting agent ethylene oxide condensate of nonyl phenol (average of 10 ethylene oxide units):

	Parts
Ammonium silicofluoride	77.678
Ammonium chloride	22.00
Ethylene oxide condensate of nonyl phenol (average of 10 ethylene oxide units)	0.300
Perfume	0.002
Calcined iron oxide paste (Caltcotine Red MB paste)	0.02

Example 2

A similar laundry sour mixture was tinted with Heliogen Blue BA-CF paste dye:

	Parts
Ammonium silicofluoride	69.695
Ammonium chloride	30.00
Ethylene oxide condensate of nonyl phenol (average of 10 ethylene oxide units)	0.300
Blue dye paste, C.I. 74,160 (Heliogen Blue BA-CF paste)	0.005

Example 3

An ester type of nonionic wetting agent, sorbitan monooleate, was used by first mixing it with Heliogen Blue BA-CF paste in 30 to 1 proportion of nonionic to dye paste and thereafter adding the dispersed dye to a mixture of laundry sour chemicals as follows:

	Parts
Ammonium fluosilicate	69.7
Ammonium chloride	30.0
Sorbitan monooleate (Span 80)	0.3
Blue dye paste, C.I. 74,160 (Heliogen Blue BA-CF dye paste)	0.01

Example 4

A mixture of ammonium fluosilicate and ammonium chloride was tinted a blue color using a dispersion of Heliogen Blue BA-CF dye paste in a fatty alkylol amide condensate as follows:

	Parts
Ammonium fluosilicate	69.7
Ammonium chloride	30.0
Alrosol C	0.3
Blue dye paste, C.I. 74,160 (Heliogen Blue BA-CF)	0.01

Example 5

A mixture of alkaline detergents was tinted a blue color with Heliogen Blue BA-CF dye dispersed in a non-

ionic wetting agent, ethylene oxide condensate of nonyl phenol (average of 10 ethylene oxide units):

	Parts
Soda ash	50
5 Sodium tripolyphosphate	50
Ethylene oxide condensate of nonyl phenol (average of 10 ethylene oxide units)	0.6
Blue dye paste, C.I. 74,160 (Heliogen Blue BA-CF)	0.02

Example 6

An alkaline detergent mixture was tinted a light blue by adding to it a dispersion of Heliogen Blue BA-CF dye paste dispersed in ethylene oxide condensate of nonyl phenol (average of 10 ethylene oxide units) as follows:

	Parts
Flake sodium hydroxide	50
Granular sodium orthosilicate	50
Ethylene oxide condensate of nonyl phenol (average of 10 ethylene oxide units)	0.3
Blue dye paste, C.I. 74,160 (Heliogen Blue BA-CF)	0.01

Example 7

A mixture of laundry sours was tinted a light green with Calcotone Green G paste dispersed in ethylene oxide condensate of nonyl phenol (average of 10 ethylene oxide units):

	Parts
Ammonium fluosilicate	69.7
Ammonium fluoride	30.0
Ethylene oxide condensate of nonyl phenol (average of 10 ethylene oxide units)	0.3
Green dye paste, C.I. 74,260 (Caltcotine Green G paste)	0.01

Example 8

The same laundry sour combination was satisfactory colored a scarlet by using 3-hydroxy-4-(4-nitrotolyl-2-azo) 2-naphthalimide dye in the same proportions and manner as the green dye paste in Example 7.

Example 9

The importance of premixing the dye paste and wetting agent was determined in the following experiments wherein dry pigment was first blended with the sour combination after which the wetting agent was added and the blending continued. No tinting of the sour mixture was obtained and instead the blue dye appeared as discreet particles throughout the sour.

	Parts
Ammonium fluosilicate	69.7
Ammonium chloride	30.0
Ethylene oxide condensate of nonyl phenol (average of 10 ethylene oxide units)	0.3
Blue dye powder, C.I. 74,160 (Heliogen Blue BWS Extra)	1.002

¹ Equivalent in solid content to pigment present in 0.01 part of Heliogen Blue BA-CF.

Similarly, when dry pigment powder and wetting agent were premixed and then blended with the laundry sour mixture, no tinting of the sours took place.

Example 10

A rust dissolving sour was satisfactorily tinted with Heliogen Blue BA-CF (blue dye paste, C.I. 74,160) dispersed in ethylene oxide condensate of nonyl phenol (average of 10 ethylene oxide units):

	Parts
70 Sodium bifluoride	50
Sodium fluosilicate	50
Ethylene oxide condensate of nonyl phenol (average of 10 ethylene oxide units)	0.6
Blue dye paste, C.I. 74,160 (Heliogen Blue BA-CF)	0.02

5

Example 11

A mixture of equal parts of zinc fluosilicate and magnesium fluosilicate was tinted in the same manner as the sours in Example 10.

Example 12

Heliogen Blue BA-CF dye paste was dispersed in a cationic wetting agent and thereafter satisfactorily used to tint a mixture of laundry sour chemicals:

	Parts
Ammonium silicofluoride	69.7
Ammonium chloride	30.0
Soybean amine polyoxyethylene condensate (Etho- meen S/15)	0.3
Blue dye paste, C.I. 74,160 (Heliogen Blue BA- CF)	0.01

Example 13

In the same manner as Example 12, stearyl amine polyoxyethylene condensate, a cationic type of wetting agent having a stearyl group and two polyoxyethylene groups totaling 5 ethylene oxide groups attached to a nitrogen atom was used to disperse calcined iron oxide paste and thereafter used to satisfactorily tint the laundry sour mixture of Example 12.

Heliogen Blue BA-CF was satisfactory dispersed in Sulfonate OS, an anionic sulfonated petroleum oil, and used to tint a mixture of laundry sour chemicals.

	Parts
Ammonium fluosilicate	69.7
Ammonium chloride	30.0
Sulfonate OS, empirical formula: $C_{25}H_{40}SO_3Na$	0.3
Blue dye paste, C.I. 74,160 (Heliogen Blue BA- CF)	0.01

Example 14

In this experiment an anionic wetting agent was used in combination with a mixture of rust dissolving sours:

	Parts
Sodium bifluoride	50
Sodium silicofluoride	50
Sulfonated castor oil T, trade name	0.6
Green dye paste, C.I. 74,260 (Calcotone Green G paste)	0.02

Example 15

A mixture of sour chemicals was satisfactorily tinted with calcined iron oxide paste (Calcotone Red MB) paste by first blending 2 parts of Calcotone Red MB paste with 2 parts of the ethylene oxide condensate of nonyl phenol (average of 10 ethylene oxide units). Thereafter an additional 28 parts of ethylene oxide condensate of nonyl phenol (average of 10 ethylene oxide units) was added to the dispersion of the wetting agent and dye paste and after intimate mixing the whole mixture was added to a mixture of 8500 parts of ammonium silicofluoride and 1500 parts of ammonium chloride. Mixing was continued in a ribbon blender until a uniform evenly tinted pink product was obtained.

6

Example 16

Calcined iron oxide (Calcotone Red MB) paste was added to a mixture of 8500 parts of ammonium silicofluoride and 1500 parts of ammonium chloride without any wetting agent. The Calcotone Red MB paste was added at 2 parts by weight. After blending for 30 minutes, no color was obtained whatsoever. Thirty parts of ethylene oxide condensate of nonyl phenol (average of 10 ethylene oxide units) was then added and mixing was continued for an additional 15 minutes. No satisfactory color was obtained from this procedure.

We claim:

1. The process of tinting a laundry chemical in the dry state, said laundry chemical selected from the group consisting of ammonium fluosilicate, zinc fluosilicate, magnesium fluosilicate, sodium fluosilicate, ammonium chloride, sodium bifluoride, sodium tripolyphosphate, sodium carbonate, sodium orthosilicate and sodium hydroxide, comprising first mixing a water insoluble dye in paste form with a liquid wetting agent selected from the group consisting of anionic, nonionic and cationic wetting agents, the ratio of dye paste to liquid wetting agent being within the range of from about 1:1 to about 1:15 by weight, and thereafter blending at least 0.005 parts by weight of the mixture of dye paste and liquid wetting agent with 100 parts by weight of said laundry chemical until the tint of said dye develops on the laundry chemical.

2. The process of claim 1 in which the water insoluble dye in paste form is selected from the group consisting of blue dye paste, C.I. 74,160, green dye paste, C.I. 74,260, calcined iron oxide paste, and 3-hydroxy-4-(4-nitro-2-azo)-2-naphthaniilide paste.

3. The process of tinting a laundry sour composition comprising dispersing water insoluble calcined iron oxide in paste form in 30 parts by weight of the ethylene oxide condensate of nonyl phenol having an average of 10 ethylene oxide units, and blending this dispersed dye with a mixture of 7,700 parts by weight of ammonium silicofluoride and 220 parts by weight of ammonium chloride until a uniform pink tint is obtained.

4. The process of tinting a laundry sour composition comprising dispersing water insoluble blue dye, C.I. 74,160, in paste form in 30 parts by weight of the ethylene oxide condensate of nonyl phenol having an average of 10 ethylene oxide units, and blending this dispersed dye with a mixture of 6970 parts by weight of ammonium fluosilicate and 3000 parts by weight of ammonium chloride until a uniform light blue tint is obtained.
